UNITED STATES PATENT OFFICE

GEORGE B. NISBET, OF CLEVELAND, OHIO, ASSIGNOR TO THE OTIS STEEL COMPANY,
OF CLEVELAND, OHIO, A CORPORATION OF OHIO

ANNEALING BOX

Application filed May 24, 1929. Serial No. 365,614.

This invention relates to an annealing box such as may contain a pack of sheet metal in an annealing furnace. The object of the invention is to provide for the more uniform heating of the contents of the box and also to increase the strength and stiffness of the box bottom, preventing its warping in the furnace heat.

It has been customary to provide annealing boxes with solid flat bottoms on which a pile of metal sheets rests. It has been found however, that with such boxes it is very difficult to satisfactorily anneal the sheets near the bottom of the pile without overannealing the sheets near the top. Not only do the sheets near the bottom fail to receive the desired amount of heat, but the bottom of the box is likely to become warped in use.

I have found that I can remedy both difficulties, producing a nearly uniform heat at the top and bottom of the box and at the same time stiffen the bottom, by providing the bottom with upwardly facing ribs or projections. These leave horizontal flues beneath the pack of sheets, enabling a circulation of the heating gases beneath and around the metal sheets during annealing. These same ribs add strength and stiffen the bottom and greatly reduce the tendency to warping.

My invention is illustrated in the drawings hereof and is hereinafter more fully described, and the essential novel features are summarized in the claim.

In the drawings Fig. 1 is a perspective, partly broken away, of an annealing box embodying my invention; Fig. 2 is a cross-section thereof showing a pack of sheets within the box; Fig. 3 is a perspective of a portion of the box bottom with a portion of a pack of sheets thereof; Fig. 4 is a fragmentary cross-section of the bottom taken at right angles to the ribs; Fig. 5 is a diagram illustrating the heating of the top and bottom portions of the pile in the ordinary flat-bottom box; Fig. 6 is a similar diagram illustrating the heating of the same parts of the pile in my improved box.

In Figs. 1 to 4, 10 indicates the bottom of the box which is provided with the usual up-standing edge wall 11. 20 indicates the top of

the box having outwardly formed stiffening corrugations or ribs 21 and being adapted to rest on the bottom of the box within the boundary wall 11 in the usual manner. In Figs. 2, 3 and 4, I have shown, on the upper 55 surface of the box bottom 10, parallel up-standing ribs 12. These ribs are shown as arranged in two sets with an aisle space 13 between them. The ribs are preferably integral with the bottom 10 and merge therewith by 60 suitable fillets 14. The ribs have their top surface 15 all in a single plane parallel with the general plane of the bottom 10. Suitable smooth aisle spaces 16 are provided on the bottom beyond the ends of the ribs and adjacent the boundary wall 11. The top rests on this smooth marginal portion and there is a clearance between the inner side of the cover and the ends of the ribs, so that the cover may be easily put in place. 70

I find that the warping can be best prevented by making the ribs diagonal, that is, extending at an angle at about 45° to the sides, and it is so shown in Fig. 3. When so directed each rib is effective in resisting distortion of the bottom about either a transverse axis or a longitudinal axis. I have shown one aisle space 13 extending longitudinally of the bottom between the sets of ribs, but more than one such space may be 80 provided if desired. It is useful in obtaining a more even distribution of the gases beneath the pack of sheets. 75

The pile of sheets indicated by A in Figs. 85 2 and 3 stands on the top surface 15 of the ribs. It will be seen that the spaces between these ribs provide a large number of flues for the passage of gases beneath the pile of sheets between the aisle spaces at the center 90 and beyond the outer ends of the ribs. Experience has demonstrated that by this means the bottom portion of the pile is heated to very nearly the same extent as the top portion, resulting in a substantially uniform annealing of the entire pile. 95

The diagrams Figs. 5 and 6, illustrating the different heating action of the old and new type of boxes are plotted from actual tests made by the use of suitably placed 100

thermo-couples over a period of approximately forty-two hours. In these views the furnace temperature is indicated by the line F; the temperature of the pack of sheets adjacent the top thereof by the line T, and the temperature of such pack a short distance above the bottom by the line B.

It will be seen from Fig. 5, that when the furnace heat was turned on at approximately 1000° F., the stack of sheets began to heat at once, with the sheets near the top heating much more rapidly than those near the bottom. The two curves T and B, it will be seen, diverged for many hours of heating. After about ten hours the furnace heat was maintained substantially uniform, as indicated by the line F, for about twenty hours. During that time the curve T continued to be a very considerable distance above the curve B. At the end of thirty hours the heat was shut off. Shortly thereafter the temperature at the top of the pack began to drop while the temperature at the bottom rose slightly, so that the two curves gradually approached each other and were nearly the same at the time of withdrawal. Now such divergence in temperature between the top and bottom portions during the larger portion of the operation results in either the bottom sheets underannealing or the top sheets overannealing.

Fig. 6 indicates the conditions within my improved annealing box. Here the furnace temperature is substantially the same as before, but the curve B, representing the temperature of the pack near the bottom has been materially raised, while the curve T representing the temperature of the pack near the top has been materially lowered so that the two temperatures run very close to each other throughout the whole operation, becoming identical a few hours after the heat is shut off and being close to each other at the end of the operation. Experience has demonstrated that with my box substantially perfect annealing is obtained throughout the entire pack of plates, the uniformity being such that after removal the plates are in substantially identical condition.

The continued heat to which annealing boxes are subjected tends to cause the parts to warp. This is not troublesome in the top but has been very unsatisfactory in the bottom as it prevents the forming of even support for the pack of sheets. With my invention however, the ribs so strengthen and stiffen the bottom that the warping is avoided.

I claim:—

A bottom for an annealing box comprising a horizontal member having integral parallel ribs extending upwardly from the bottom of the box, said ribs extending diagonally in a plurality of sets separated by an

aisle space providing a longitudinal flue for gases.

In testimony whereof, I hereunto affix my signature.
